Filed Sept. 14, 1964, Ser. No. 396,294
12 Claims. (Cl. 292—53)

This invention relates to latch mechanism for swinging doors, especially the doors of automobile or other vehicle bodies.

Of current interest in automotive design is the use of double-jaw latching mechanisms in which a striker pin is engaged between a pair of opposed jaws to maintain the vehicle door in latched condition. The present invention is embodied in an improved latch mechanism of this general category, and comprises a pair of opposed latching jaws or elements pivotally supported on the main plate portion of the latch mechanism. Both of the latching jaws are fixedly coupled to control or ratchet plates which are engageable by pivoted detent or pawl means for holding the latching jaws in latched position. The latch mechanism includes improved inner and outer manually operable actuating means for simultaneously swinging or pivotally actuating the detent or pawl means to disengage the same from the control or ratchet plates. Also included are improved control means for selectively controlling the effectiveness of the outer manually operable actuating means in the actuation thereby of the detent or pawl means.

An object of the present invention is to provide an improved door latch mechanism which will effectively meet various requirements for vehicle door locks, which is characterized by simplification and compactness in construction, which is easy and economical to manufacture, and which is comparatively quiet, reliable and durable in use.

Further objects and features of the particular embodiment of the invention herein illustrated will appear in the following description, reference being had to the accompanying drawing forming a part of the specification wherein like reference numerals designate corresponding parts in the several views.

FIG. 1 is a sectional elevation taken substantially through lines 1—1 of FIG. 2 illustrating a door latch mechanism constructed in accordance with a preferred embodiment of the invention;

FIG. 2 is a sectional elevation taken substantially through lines 2—2 of FIG. 1; and

FIG. 3 is an elevation of the door latch mechanism taken from the side opposite to that shown in FIG. 1.

Before explaining in detail the present invention, it is to be understood that the invention is not limited in its application to the details of construction and arrangement of parts illustrated in the accompanying drawing, since the invention is capable of other embodiments and of being practiced or carried out in various ways. Also, it is to be understood that the phraseology or terminology employed herein is for the purpose of description and not of limitation.

In the drawing there is illustrated, by way of example, a certain embodiment of the present invention as adapted to be applied to door and door frame structures of an automobile body. The latch mechanism comprises a case plate 11 which is adapted to be secured, as by means of screws, to the inner side of the jamb portion or free edge wall of a vehicle door (not shown), the case plate 11 having a flange 12 which is adapted to be positioned along an inner panel of the door. The present latch mechanism has a pair of pivoted latch devices comprising jaw elements 13 (see FIG. 3) positioned at the outer face of the case plate 11. Each jaw element 13 is provided with an integral shaft or pivot portion 14 which extends

2

through a suitable flanged aperture (not visible) in the case plate. Suitable bearing means (not shown) are provided within flanged aperture for journaling each pivot shaft 14 for pivotal movement and for holding the jaw elements on the plate portion. Each jaw element 13 is keyed or otherwise fixedly coupled through its pivot shaft 14 to a control plate 15, for a purpose to be hereinafter explained. Each jaw element 13 and its related control plate 15 for the purpose of definition may be considered 10 a "latch device means."

Each jaw element 13 is a substantially triangular plate member having its pivot axis located near its apex. The base side or the side 16 opposite the apex is provided in the center with a semi-circular recess or enlarged notch 15 17 adapted to encompass a cylindrical striker or keeper pin (not shown).

Each control plate 15 is provided with two peripherally spaced abutments or ratchet teeth 18 and 19. Cooperable with the abutment or ratchet toothed edge of the lower 20 control plate 15 is a swingable multi-armed detent or pawl means, generally designated 21, pivotally mounted on a shoulder rivet 22 secured to the case plate 11. The detent means 21 has a vertically depending arm 23, the end portion 24 of which functions as an abutment or 25 detent engaging portion cooperable with the teeth or abutments 18 and 19 on the lower control plate 15. It will be noted further that the detent or pawl means 21 is located above the lower control plate 15, that the ratchet teeth or abutments 18 and 19 are located on the side 30 peripheral surface of the lower control plate 15, and that the end portion 24 of the detent depends from the pivot axis of the detent means in position to engage either of the ratchet teeth 18 or 19.

The upper control plate 15 is substantially similar to 35 the lower control plate 15 but is placed on its pivot shaft in inverted relation to the lower control plate. Cooperable with the abutment or ratchet-toothed edge of the upper control plate 15 is a swinging detent or pawl 25 pivotally mounted on a pivot stud or shoulder rivet 26 secured to the case plate 11. The detent or pawl 25 is provided with an arm 27 which extends in the general direction of the flange 12. It has a second arm 28 which curves downwardly from the pivot stud 26 and terminates in a hook-like portion 29 which functionally is the equivalent of the abutment portion 24 of the arm 23 of the detent means 21.

When the detent means arm 23 abutment portion 24 and the hook portion 29, respectively, are in position to engage the lower and upper control plate abutments 18, 50 the jaw elements 13 will be held in what is known as a secondary latched position. When in this secondary latched position, the relationship of these jaw elements to a striker or keeper pin creates sufficient interference to prevent opening movement of the vehicle door. The door will not, however, be held against vibratory movement in a vertical direction, and it is expected that the rattling noise that will ensue as the vehicle is driven about will call the occupant's attention to the fact that the door is not fully latched. When the abutment portion 24 and the hook portion 29 are in position to engage the respective control plate abutments 19, as seen in FIG. 55 1, both jaw elements 13 will be held in final or fully latched position.

The detent 25 is directly coupled to the detent means 60 21 by a link 31. The detent means 21 has an arm 32 which extends in a substantially horizontal direction toward the flange 12 of the case plate 11. The lower end of the link 31 is pivotally connected to the arm 32 by a pivot stud 33 and the upper end to the arm 27 of the detent 25 by a pivot stud 34.

Both detents are urged in a clockwise or control plate 65 engaging direction by a common or single spring 35. The

spring 35 is a tension spring anchored at its upper end to a stud 36 secured to the case plate 11 and at its lower end to a stud 37 fastened to the arm 32 of the detent means 21. The spring 35 urges the arm 32 of the detent means 21 upwardly, and the force of the spring is transmitted through the link 31 to the arm 27 of the detent 25. The arm 27 is thus urged upwardly and this results in the arms 23 and 28 correspondingly being urged in detent engaging direction toward the lower and upper control plates, respectively.

To permit unlatching movement of the jaw elements 13, the end portion 24 of the detent means arm 23 and the hook portion 29 of the detent arm 28 must be moved out of abutting relation to the control plate abutments 19 and 18. This may be accomplished from either the outside or the inside of the vehicle door through actuation of the detent means 21. By actuation of the detent means 21 is meant the swinging of the latter in a counterclockwise direction (as viewed in FIG. 1) against the resistance of the spring 35. Because of the link 31, such counterclockwise swinging movement of the detent means 21 is transmitted to the detent 25 causing corresponding counterclockwise swinging movement of the latter.

For actuation from the outside of the vehicle door the detent means 21 has an upstanding arm 38 terminating in a flange 39. The flange 39 lies in the path of the inwardly movable stem 41 of a pushbutton or the like mounted in a door handle assembly fastened to the exterior surface of the outer door panel (not shown). This follows conventional practice in the art.

For actuation from the inside of the vehicle door, the detent means 21 has an extension 42 on its arm 32. This extension 42 is offset away from the case plate 11 and slightly projects through a slot 43 in the case plate flange 12. The extension 42 underlies a substantially horizontally extending arm 44 of a bell crank lever 45 pivotally mounted on a pivot stud 46 on the case plate flange 12.

The slot 43 in the case plate flange 12 functions as a guide for the end of the arm 32 and also limits its range of upward and downward movement. This eliminates the need of any additional stops for controlling the range of movement of the detent means 21.

The bell crank lever 45 is provided with a second or substantially vertically depending arm 47 adapted to be coupled by a draft link (not shown) extending to a remote control mechanism (not shown) mounted on the inner panel of the door. When the bell crank lever 45 is swung in a clockwise direction, as viewed in FIG. 2, its arm 44 will swing downwardly thereby depressing the arm 32 of the detent means 21. This arm 32 movement will result in the end portion 24 of the detent means arm 23 being moved out of engagement with the lower control plate 15. As happened when the pushbutton stem 41 was actuated to cause counterclockwise movement of the detent means 21, counterclockwise movement of the detent means 21 resulting from actuation of the bell crank lever 45 results in counterclockwise movement of the detent 25 and therefore disengagement of the hook portion 29 from the upper control plate 15.

Provision is made for "locking" the latch mechanism to prevent disengagement of the detents from the control plates holding the latch jaws in latched position, the position shown in FIG. 3. In the present latch mechanism, this is accomplished by means of a locking lever (see FIG. 2). This locking lever, generally designated 48, has a pair of arms 49 and 51 which are in generally V-shaped relationship to each other. The locking lever 48 is pivoted at the apex of the V to the case plate flange 12 on a pivot stud 52. The locking lever arm 49 extends at an angle downwardly toward the case plate 11 and passes between the offset extension 42 of the detent means arm 32 and the case plate 11. This arm 49 terminates in a hook-like portion 53 which is adapted to pass under the extension 42 of the detent means arm 32. It will be

understood that it is placed under the extension 42 only when it is desired to render the outer manually operable push button stem 41 inoperable to release the detents or pawls from the control plate abutments 19.

The hook-like portion 53 is movable into blocking position relative to the extension 42 by actuation of the bell crank lever 45. As seen in FIG. 2, the arm 44 of the lever 45 is adapted to abut a lug or projection 54 on the lower end of the arm 51 of the locking lever 48. It should be understood that the latch mechanism embodying the present invention is intended to be used with a remote control mechanism which may be operated to swing the lever 45 not only in a clockwise but also in a counterclockwise direction, as desired, and to hold it after movement in the counterclockwise direction in locking position. As has been described, when swung in a clockwise direction the lever 45 is operable to disengage the detent means 21 and the detent 25 from the control plate 15 abutments. When swung in a counterclockwise direction, the arm 44 of the lever 45 will abut the lug 54 on the arm 51 of the locking lever 48 swinging the latter in a clockwise direction to position the hook-like portion 53 under the extension 42 of the detent means 21 arm 32. The remote control mechanism of necessity must be of the type which will positively hold the lever 45 in its counterclockwise displaced position against the resistance of a spring 55 which encompasses the pivot 52 of the locking lever 48 and urges the latter at all times in unlocked direction.

When the locking lever 47 is in latch mechanism 30 "locked" position, the detent means 21 is rendered immovable. When the detent means 21 is held against movement, the outer manually operable means (push button stem 32) cannot be actuated to cause disengagement of the detents or pawls from the respective control plates 15. 35 The latch mechanism may, however, always be released from the inside of the vehicle door. Actuation of the inner manually operable means (bell crank lever 45) from door locked position first results in movement of the locking lever 48 under the influence of the spring 55 to non-locking position (FIG. 2). The bell crank arm 44 then picks up the arm 32 of the detent means 21 causing the latter and also the detent 25 to be swung in detent disengaging direction.

The present latch mechanism cannot be placed in 45 "locked" condition when the jaw elements 13 are in unlatched condition. The relationship of the detent portion 24 and hook 29 of the detents to the cam surfaces 56 of the control plates is such that the detents are displaced away from the control plates when the jaw elements and the control plates are in latch mechanism unlatched position. The displacement of the detent means 21 results in a downward displacement of its arm 32 to an extent sufficient to position the side face of the extension 42 in the path of the hook-like portion 53 of the locking lever 48. 50 The latter cannot be moved into its locking position shown in FIG. 2 until the extension 42 is moved out of the way of the hook-like portion 53, as occurs when the jaw elements and control plates are moved to fully latched position.

60 The foregoing also applies to a situation in which the jaw elements are in secondary latched position, i.e., when the jaw elements are in a position in which the detents are holding the control plates against movement in unlatching direction through engagement of the detent abutment portions 24 and 29 with the ratchet teeth 18. The depth or undercut forward of each ratchet teeth 18 is such that the detents are displaced from their fully latched position to an extent sufficient to cause interference between the detent means arm 32 extension 42 and the hook-like portion 53 of the locking lever 48. 65 Thus, in secondary latched position of the jaw elements the locking lever 48 cannot be moved into locking position.

To complete the physical description of the present 70 latch mechanism, attention is called to the tension spring

56 extending between the upper and lower control plates 15. When the parts of the latch mechanism are in the relationship shown in FIG. 1, the spring 56 is extended or under maximum tension. Upon disengagement of the 5 detents from the control plates, the spring 56 will pull both control plates and thereby both jaw elements 13 toward their unlatched positions. Upon the jaws 13 engaging a striker pin as the vehicle door is moved from an opened to a closed position, the control plates 15 will be rotated in counter directions against the resistance of the spring 56 to again place the latter under increased tension.

The latch elements are mounted in an appropriate housing 57 (see FIG. 3). The wall surfaces 58 and 59 of the housing on each side of the opening through which the striker or keeper pin is admitted acts as a stop to limit the movement of the latch elements in opening direction and to insure that the latch elements are positioned so that they will be ready to engage the striker pin as the door is moved from an open to a closed position. As the door is moved to a closed position, the striker pin will seat in one or the other of the recesses 17. This causes the strike pin to be guided into engagement with the recess 17 in the other jaw element so that both jaw elements fully engage the striker pin on opposite sides 25 as they are swung against the resistance of their respective springs toward the fully latched position shown in FIG. 3. The detent abutment portion 24 and the detent hook portion 29 will then engage the control plate ratchet teeth 18 or 19 so that the jaw elements are restrained 30 against movement L-9/N in an unlatching direction.

In fully latched position, the center of the striker pin will be located substantially at the center of the circular notches or recesses 17. In fully latched position this center lies over center from a line drawn between the pivot axes of the two jaw elements. This relationship is such that any forces tending to separate the two jaw elements will not be in the direction of opening movement of the door but will be rather in the direction of closing movement, and thus the tendency would be to urge the door 40 more fully in a closed direction.

I claim:

1. In a latch mechanism for a swinging door, a support having a plate portion for disposition at the free edge wall of the door, a pair of latch device means pivotally mounted on said plate portion for counterswinging movement from an unlatched position to a latched position. 45 a pair of detent means each pivotally mounted on said plate portion for engagement with a respective one of said latch device means to hold the same in latched position, coupling means coupling said detent means to each other for movement in unison to and from latch device means engagement, said coupling means comprising a link pivotally connected at each of its ends to a respective one of said pair of detent means, 55 and manually operable means engageable with one of said detent means to actuate the same and thereby the other of said detent means in detent disengaging direction.
2. In a latch mechanism according to claim 1 in which: a locking lever pivotally mounted on said support is engageable with one of said detent means to prevent 65 disengagement of the same and thereby said other detent means from said latch device means.
3. In a latch mechanism according to claim 2 in which: a spring means coupled to one of said detent means 70 urges both detent means toward latch device means engagement.
4. In a latch mechanism according to claim 1 in which: said one of said detent means comprises a multi-arm member,

one of the arms of said multi-arm member extending in latch device means engaging direction, another of the arms being engaged by the manually operable means, and the manually operable means is operable from the outside of the door.

5 5. In a latch mechanism according to claim 4 in which: a locking lever is pivotally mounted on said support and is engageable with said one of said detent means to prevent disengagement of the same and thereby said other detent means from said latch device means by the manually operable means.

10 6. In a latch mechanism for a swinging door, a support having a plate portion for disposition at the free edge wall of the door, a pair of latch device means pivotally mounted on said plate portion for counterswinging movement from an unlatched position to a latched position, a pair of detent means each pivotally mounted on said plate portion for engagement with a respective one of said latch device means to hold the same in latched position, coupling means coupling said detent means to each other for movement in unison to and from latch device means engagement, said coupling means comprising a link pivotally connected at each of its ends to a respective one of said pair of detent means, one of said detent means comprising a multi-arm member having a first arm extending in a latch device means engaging direction and a second arm extending at an angle thereto, outer manually operable means engageable with said second arm to pivot said one detent means and thereby the other of said detent means out of engagement with the respective latch device means.

20 7. In a latch mechanism according to claim 6 in which:

a locking lever pivotally mounted on said support is engageable with one of said detent means to prevent disengagement of the same and thereby said other detent means by said outer manually operable means.

25 8. In a latch mechanism according to claim 7 in which:

a spring means coupled to one of said detent means urges both detent means toward latch device means engaging position.

30 9. In a latch mechanism for a swinging door, a support having a plate portion for disposition at the free edge wall of the door, a pair of latch device means pivotally mounted on said plate portion for counterswinging movement from an unlatched position to a latched position, a pair of detent means each pivotally mounted on said plate portion for engagement with a respective one of said latch device means to hold the same in latched position, said detent means being coupled to each other for movement in unison to and from latch device means engagement,

35 one of said detent means comprising a multi-arm member having a first arm extending in latch device means engaging direction and a second and a third arm, outer manually operable means engageable with said second arm and inner manually operable means engageable with said third arm to actuate said one detent means and thereby the other of said detent means in detent disengaging direction, and a locking lever pivotally mounted on said support engageable with said third one of said multi-arms to prevent movement of said one of said detent means and thereby said other detent means in detent disengaging direction by said outer manually operable means.

10. In a latch mechanism according to claim 9 in which:

said locking lever is moved into locking position in response to movement of said inner manually operable means in a direction opposite to that in which the latter is movable to cause detent disengaging movement of said pair of detent means.

11. In a latch mechanism according to claim 10 in which:

the coupling between said pair of detent means comprises a link extending from said third arm to an arm on said other detent means.

12. In a latch mechanism according to claim 11 in which:

a spring means coupled to said third arm urges both detent means toward latch device means engaging position.
